UNITED STATES PATENT OFFICE

GEORGE A. JOHNSON, OF CHICAGO, ILLINOIS, ASSIGNOR TO W. H. MINER, INC., OF CHICAGO, ILLINOIS, A CORPORATION OF DELAWARE

HAND BRAKE

Application filed November 4, 1927. Serial No. 230,945.

This invention relates to improvements in hand brakes.

In the operation of geared mechanisms of certain types, excessive friction is developed between the gear teeth because of the difficulty in accurately placing the axes of rotation of the gears, resulting in failure to provide efficient meshing engagement of the gear teeth at the pitch diameters thereof, and particularly is this true in hand brake mechanisms for railway cars wherein the gears are seldom mounted in an accurate manner, and, even if so mounted, quickly lose accurate engagement because of distortion and wear.

An object of this invention is to provide a hand brake mechanism including meshing gears which are automatically maintained in proper meshing relation, and which do not depend for efficient operation upon the accurate placing of the spindles upon which they rotate.

A more particular object of the invention is to provide a hand brake mechanism of the character indicated, wherein the axis of rotation of only one of the meshing gears is fixed, while the axis of the other gear is movable with reference to the axis of the first gear, the axis of the movable gear being urged toward the stationary axis of the other gear under the influence of the pull of the brake chain on the winding drum, and maintained in proper spaced relation for the most effective meshing of the teeth of the gears by means of shrouds on the gears which support the load.

Other and further objects of the invention will more clearly appear from the description and claims hereinafter following.

In the drawings forming a part of this specification, Figure 1 is a front elevational view of the hand brake mechanism embodied in the invention, showing the hand wheel in dotted lines. Figures 2 is a transverse, vertical, sectional view of the invention, corresponding substantially to the line 2—2 of Figure 1. And Figure 3 is a vertical, sectional view of the invention taken on the line 3—3 of Figure 2.

As shown in the drawings, 10 represents a fragment of the end wall of a railway car,

and secured to said wall is a support indicated broadly by the numeral 11. The support comprises an inner wall 12, having an extension 13 at its upper end secured to the wall 10 of the car by means of rivets indicated at 14. Formed integrally with the upper portion of the wall 12 is a top wall 15, at the opposite ends of which are integrally formed side walls 16 and 17.

The top wall 15 is provided with an angularly disposed flange 18, to which an outer plate 19 is secured by means of rivets indicated at 20, the plate 19 being provided with angular extensions 21, the top flange 22 of which bears against the under surface of the top wall 15, while the vertical flange 23 thereof bears upon the adjacent side wall of the support and is secured thereto by rivets indicated at 24.

The plate 19 is provided with a centrally disposed boss 25, defining a bearing opening 26, in which is rotatably mounted a short shaft 27, on the outer end of which is secured a hand wheel 28. Preferably formed integrally with the inner end of the shaft 27 is a pinion 29. The pinion 29 is provided with an annular series of gear teeth 30, and upon opposite sides of the gear teeth are formed shrouds 31—31, said shrouds being annular in form and having their outer peripheries coinciding with the pitch diameter of the gear teeth 30 of the pinion. The inner wall 12 is provided with a spindle 32 disposed axially in line with the shaft 27, and rotatably mounted upon the spindle 32 is an annular roller 33, of a diameter corresponding to the diameters of the shrouds 31 of the pinion 29.

The pinion 29 and roller 33 serve as a support for a winding drum 34. Said drum is preferably tapered in form, being of the largest diameter at its outer end, and gradually tapering towards its inner end, and is provided with a helical thread 35 adapted to guide the brake chain, indicated at 36, when same is being wound upon the drum, the chain 36 being connected to the drum by means of an eye member indicated at 37, said chain being connected to the brake shoes proper. Formed integrally with the outer end of the drum 34 is a cup-shaped member 100

38, of relatively large diameter as compared with the diameter of the drum 34, said cup-shaped member 38 being in the form of an internal ring gear having a central annular series of teeth 39 adapted to mesh with the teeth 30 of the pinion 29, and at each side of the gear teeth 39 there are provided annular shrouds or bearing portions 40—40, which coincide with the pitch diameter of the teeth 39, and are adapted to bear upon the annular shrouds 31—31 on the pinion 29. The opposite end of the drum is provided with a cup-shaped member 41, which has an internal annular tread 42, adapted to bear upon the tread of the roller 33. Each of the cup-shaped members 38 and 42 is provided with an outwardly extending boss indicated at 43 and 44, respectively, the drum 34 and the bosses 43 and 44 being provided with a central bore adapted for the reception of an axle 45, the inner end of the axle being supported in an elongated plate 46 disposed in an elongated slot 47 in the wall 12, to permit limited sliding movement of the plate and axle in a vertical direction. The outer end of the axle 45 is likewise mounted in an elongated plate 48, which is slidably mounted in a slot 49 in the front wall 19 of the support, a cotter pin 50 extending through the end of the axle as shown.

Means are provided for preventing retrograde rotation of the winding drum 34, said means including a pawl 51 adapted to engage the gear teeth 39 of the ring gear 38, preferably at the lower end thereof, as shown, said pawl having a lateral trunnion member provided with a cylindrical bearing portion 52 rotatably mounted in an opening in the outer wall 19 of the support. Outwardly of the cylindrical bearing portion, the trunnion is formed with a shank portion 53 of square cross section upon which is mounted an operating lever or portion 53 upon which is mounted an operating lever or handle 54, held in position by a cotter pin 55, the handle being so arranged with reference to the pawl 51 that the weight of the handle normally maintains the pawl 51 in engagement with the teeth 39 of the gear 38, while permitting the pawl to ratchet over the teeth 39 when the chain is being wound upon the drum.

In operation, clockwise rotation of the hand wheel 28 effects corresponding clockwise rotation of the pinion 29, which transmits its movement to the gear 38 through the inter-engagement of the teeth 30 of the pinion therewith, resulting in rotation of the drum 34 in a clockwise direction. During this movement the pull of the brake chain 36 on the drum 34 urges the gear 38 toward the pinion 29, the axle 47 being free to move downward as permitted by the movement of the plates 46 and 48 in the slots 47 and 49,

the slots confining any movement which occurs to a vertical direction. The opposite end of the drum 34 is supported through the engagement of the annular bearing surface 42 of the member 41 upon the roller 33. The meshing of the teeth 30 and 39 of the pinion 29 and gear 38, is governed by the provision of the shrouds 31—31 of the pinion 29, and 40—40 of the ring gear 38, said shrouds maintaining meshing of the teeth of the gears at their pitch diameters, and serving as supporting means for the drum at one side thereof. While drum 34 is being wound in a clockwise direction to take up the chain, the pawl 51 will ratchet over the teeth 39 of the gear 38, as permitted by the pivotal mounting thereof and the disposition of the handle 54, retrograde rotation of the gear 38, and consequently of the drum 34, being prevented by the normal engagement of the pawl 51 with the teeth of the gear 38. When it is desired to release the brake, the handle 54 is pulled in a clockwise direction, permitting unwinding of the chain from the drum 34 through counter-clockwise rotation of the gear 38, drum 34 and member 41.

While I have herein shown and described what I consider the preferred manner of carrying out the invention, the same is merely illustrative, and I contemplate all changes and modifications which come within the scope of the claims appended hereto.

I claim:

1. In a hand brake mechanism of the character described, the combination with a winding drum having oppositely disposed annular cup-shaped members, each of which is provided with an annular bearing surface; an element extending into each of said cup-shaped members, each of said elements being of smaller diameter than said cup-shaped members and mounted in spaced relation and co-axially to rotate about relatively fixed axes; and means for mounting said drum to effect rotation thereof about the central axis thereof and the central axis of said cup-shaped members, said means including an axle for said drum and fixed supports in which the ends of said axle are slidably mounted, said drum being arranged whereby the load imposed upon the drum by the brake chain is borne by said cup-shaped members and said rotatable elements.

2. In a hand brake mechanism of the character described, the combination with a winding drum having an internal ring gear rigidly affixed thereto and rotatable therewith; means for supporting said drum for rotation about a central axis; a pinion engaging said ring gear for driving said drum; and a locking pawl disposed within the ring gear also engageable with the internal teeth thereof to prevent retrograde rotation of the same, said pawl having an

operating handle exteriorly of the gear by which the same may be manipulated.

3. In a hand brake mechanism of the character described, the combination with a support providing spaced vertical walls, having vertically extended elongated slots therein; of a winding drum provided with oppositely disposed cup-shaped members at its ends, one of which is in the form of an internal ring gear, and the other of which is provided with a smooth annular engaging portion, said drum having an axle the ends of which are slidably mounted in the slots in said support; a roller mounted to rotate about a fixed axis with reference to the wall adjacent the cup-shaped member having the smooth annular bearing surface, said roller being disposed in supporting relation with respect to said bearing surface; a pinion co-operating with said ring gear, said pinion being rotatable about a relatively fixed axis arranged co-axially with reference to the axis of said roller, said pinion being disposed in supporting relation with said ring gear, and the teeth of said pinion meshing with the teeth of the ring gear; and a gravity influenced pawl engageable with the teeth of said ring gear to prevent retrograde rotation thereof.

4. In a hand brake mechanism of the character described, the combination with a support providing spaced vertical walls, having vertically extended elongated slots therein; of a winding drum provided with oppositely disposed cup-shaped members at its ends, one of which is in the form of an internal ring gear, and the other of which is provided with a smooth annular engaging portion, said drum having an axle the ends of which are slidably mounted in the slots in said support; a roller mounted to rotate about a fixed axis with reference to the wall adjacent the cup-shaped member having the smooth annular bearing surface, said roller being disposed in supporting relation with respect to said bearing surface; a pinion co-operating with said ring gear, said pinion being rotatable about a relatively fixed axis arranged co-axially with reference to the axis of said roller, said pinion being disposed in supporting relation with said ring gear, and the teeth of said pinion meshing with the teeth of the ring gear, said ring gear and said pinion being provided with shrouds which support the load and assure meshing engagement of the teeth of said pinion and ring gear at their pitch diameters.

5. In a hand brake for railway cars, the combination with a winding drum having bearing members at opposite ends thereof, presenting interior annular bearing surfaces; of a pair of rotatable supporting members rotatable about aligned horizontal axes engaging within said annular bearing members and suspending the same to support said winding drum and forming the usual supporting

means for said drum, one of said rotatable members and the cooperating bearing members being in driving engagement; manually operated means for rotating said last named rotatable member to effect winding movement of the drum; and a brake tightening element connected to the drum and suspended therefrom, said tightening element being connected to the brake mechanism proper of the car.

6. In a hand brake for cars, the combination with a chain winding drum having a bearing member fixed thereto, said drum and bearing member being rotatable about a common axis, said bearing member being of ring-like form and having an interior annular bearing surface; a cylindrical bearing member supported for rotation about a horizontal axis eccentric to said first named axis, said cylindrical bearing member engaging within said ring-like member and supporting the latter and said drum, said cylindrical member and the ring-like member being in driving engagement; and a brake chain connected to the drum and suspended therefrom, said brake chain being operatively connected to the brake mechanism proper of the car.

In witness that I claim the foregoing I have hereunto subscribed my name this 1st day of November, 1927.

GEORGE A. JOHNSON.
